UNITED STATES PATENT OFFICE.

CHARLES ALBONESI, OF DUMONT, NEW JERSEY.

SASH-LOCK CONSTRUCTION.

1,394,513.

Specification of Letters Patent. Patented Oct. 18, 1921.

Application filed October 22, 1920. Serial No. 418,841.

To all whom it may concern:

Be it known that I, CHARLES ALBONESI, a citizen of the United States, residing in Dumont, Bergen county, State of New Jersey, have invented certain new and useful Improvements in Sash-Lock Construction, of which the following is a specification.

My invention relates to a sash lock construction for windows whereby the sashes 10 may readily be locked in closed position or may be permitted an unrestricted sliding movement, or a limited sliding movement, in relation to each other. In accordance 15 with my invention a manipulative device is provided having several positions, in one of which the sashes are free to slide past each other for a limited, determined, distance only. Thus, it is possible to leave the window open for ventilation with the assurance that 20 the limited amount of opening provided will not be sufficient to enable an intruder to enter through the same. A person on the outside may, of course, reach through the opening and attempt to manipulate the locking 25 device. This will, however, avail him nothing since the locking device can only be so positioned as to permit moving the same into a position in which the sashes have an unrestricted sliding movement, when the sashes 30 are both entirely closed. This being the case a person on the outside can never effect an opening sufficient to admit his body without breaking the glass.

I obtain this result by providing one of 35 the sashes with a vertical guideway which extends for a part only of the height of the sash. The other sash is provided with a horizontal opening therethrough in which is slidably mounted a spindle having a head 40 which may be aligned with the vertical guideway, only when the meeting rails of the two sashes are in meeting position. The arrangement is such that the head of the spindle cannot be removed from the guideway 45 in any way except by movement of the spindle through the horizontal opening referred to, when the two sashes are entirely closed. The sash may be locked in closed position by moving the head of the spindle 50 into a socket which is aligned therewith when the two sashes are entirely closed. The head of the spindle may also, when the sashes are

closed, be moved into a position in which unrestricted sliding movement of the sashes is permitted. Means are also provided for 55 locking or holding the spindle in each of the three positions referred to.

In order that my invention may be more clearly understood attention is hereby directed to the accompanying drawings forming part of this application and illustrating one embodiment of my invention. In the drawings Figure 1 represents a front elevation of a window, viewed from the inside of the room, and provided with my invention, 60 Fig. 2 represents an enlarged vertical section taken on line 2-2 of Fig. 1, Figs. 3 and 4 are partial sections similar to that shown in Fig. 2, showing the locking spindle in different positions, Fig. 5 represents 65 a vertical section taken on line 5-5 of Fig. 2, Fig. 6 represents a partial vertical section taken on line 6-6 of Fig. 4, and Fig. 7 is a detail construction showing the lock barrel and escutcheon plate, partly in side 70 elevation and partly in section.

Referring to the drawings, I have illustrated a window having an upper sash 1 and a lower sash 2 slidably mounted in the usual manner in a frame or casing indicated 80 at 3. The upper sash 1 is provided with a bottom rail 4 and the lower sash with a top rail 5, these rails meeting in the usual manner, as indicated at the line 6, when the two sashes are closed.

One of the vertical side members or stiles of the upper sash is provided with a vertical guideway 7 which extends upwardly for a limited distance from the bottom rail of the sash. This guideway communicates 90 at the bottom with a horizontal opening 8 which extends into rail 4 for a short distance. Rail 5 is provided with a horizontal opening 9 therethrough which aligns with the opening 8 when rails 4 and 5 are in 95 meeting position.

Opening 9 is provided at one of the upper corners of the frame of the lower sash, preferably on the line where the rail and stile are joined together. In the preferred construction, a lock barrel 10 is mounted within opening 9, this barrel having a front flange 11. An escutcheon plate 12 is secured to the front or inner face of the rail, in front

of flange 11, this plate having a forwardly extending sleeve portion 13 which is coaxial with barrel 10.

The lock spindle 14 is slidably mounted 5 within barrel 10 and through a suitable opening in escutcheon plate 12. The spindle is provided with a head 15 which is adapted to be alined with the guideway 7. Barrel 10 is provided at its rear, that is its outer 10 end, with a key hole slot 16. The cylindrical or body portion of the spindle is slidably and rotatably mounted in the main or cylindrical portion of this slot, as well as in the opening referred to in escutcheon plate 15 12. The spindle is provided with laterally extending projections 17, 18 and 19, in alinement with each other. The key projections 17 and 18 are adapted to be passed through the vertical portions of the key hole slot, 20 when the spindle is in proper position to aline these projections with the slot.

A knob 20 is provided having an annular flange 21 within which the forward end of spindle 14 is received, the spindle and knob 25 being secured together by a screw 22. A sleeve 23 is provided which is secured to knob 20, preferably by a screw-threaded engagement as shown. Sleeve 23 is slidably mounted on the collar or annular extension 30 13 of escutcheon plate 12.

A spiral spring 24 is preferably positioned upon spindle 14, to press the same rearwardly, that is, outwardly of the window. This spring may be arranged to bear 35 against escutcheon plate 12 at one end, and against the key projection 19 on the spindle at the other end, as shown. The opening 8 in sash 4 is preferably provided with a lining plate 25. Opening 8 is extended rearwardly as shown to form a socket 26 in 40 which the head 15 may be received when the sashes are to be locked together in closed position.

The guideway 7 is preferably provided 45 with a rear wall 27 and with front walls 28 between which a vertical slot 29 is provided of a width sufficient to permit the movement of spindle 14 up and down the same while the plates 28 prevent movement of head 15 50 forwardly past the same, when it is within the guideway. The guideway is provided with a top wall 29, so that head 15 may only be removed from the guideway by closing the sashes to aline openings 8 and 9 so that 55 head 15 may be moved horizontally below the lower end of flanges 28.

With the arrangement described, when the sashes are closed as is shown in Fig. 2, knob 20 being in vertical position, key projections 17 and 18 will pass through key slot 16 and head 15 will enter socket 26, this movement being caused by spring 24 if the knob is not held. In this position the sashes will be locked against any movement. 60 The spindle may be locked against removal

from this position by turning the same into horizontal position, that is by turning the same through an angle of 45 degrees. In the construction shown in the drawings, the knob is turned to the right through an angle 70 of 45 degrees whereupon key projection 19 will abut against a stop 30. The spindle cannot be withdrawn from this position until it is turned back to the vertical position, because of the fact that projection 18 75 is out of alinement with key slot 16.

When the sashes are to be given a limited amount of opening, if the sashes have previously been entirely locked, the knob 20 is drawn inwardly into the position in which 80 head 15 is in alinement with guideway 7. In this position projection 17 will be at the rear of the key slot and projection 18 will be immediately in front of the key slot.

Knob 20 may then be rotated 45 degrees to 85 the right, as shown in Fig. 3, whereupon projection 18 will abut against stop 30 and the spindle will be locked to the barrel by projections 17 and 18, which are positioned on opposite sides of the bottom of the barrel. The position in which head 15 alines with guideway 7 may readily be indicated as by means of a circumferential groove or 90 mark 31 extending about the annular projection 13 of escutcheon plate 12. The knob 95 may be moved either inwardly or outwardly, depending on its previous position, until the end of sleeve 23 alines with the groove or mark 31, whereupon the knob may be rotated into position to lock the spindle 100 to the barrel as stated.

When it is desired to have the sashes entirely free to slide up and down, the sashes being in closed position, knob 20 is drawn forwardly as far as it will go, whereupon it 105 is turned 45 degrees to the right into the position shown in Fig. 4. In this position head 15 is in front of guideway 7 so that no obstruction is offered to the free movement of both sashes. The spindle is locked 110 in this position by projection 17 on one side of the bottom of barrel 10 and the head 15 on the other side of the same.

It will be noted from the above that the 115 sashes may be kept open to the extent permitted by the guide slot while a greater amount of sliding movement of the sashes is prevented by a manipulative device, the position of which cannot be altered except when both sashes are closed, and in that 120 case, only from the inside. To move the spindle from any one of the three positions into any other one of said positions, the two sashes must be closed. It is accordingly impossible to manipulate the locking device by 125 a knife or other instrument, from the outside of the window. It may also be noted that the arrangement described leaves the panes of both sashes entirely clear for cleaning, since the lock is mounted on the frame 130

of the sashes, at one side, where it presents no obstruction to cleaning of the panes.

It may also be noted that spring 24 is of use in the ready manipulation of the device 5 but that the device will remain entirely operative if the spring should be broken. It will also be noted that the device is of simple and inexpensive construction and readily mounted upon or removed from an existing window construction.

To mount the device in position, the nail 15 which is ordinarily found at the mortised connection between either stile and the bottom rail of the top sash, and the corresponding nail at the connection between the stile and the top rail of the bottom sash are taken out. These nails are usually put in the sashes at the mortise connections when the same are being glued together.

20 The hole 9 is then bored through the rail 5 of the bottom sash, at the point at which the nail referred to was located. This hole should then be counter-sunk to a depth equal to the thickness of barrel flange 11 and 25 escutcheon plate 12. Barrel 10 is then mounted within opening 9 and fastened in position by a screw through flange 11 of the barrel. The spindle is then inserted through the barrel and through the key slot 30 16 whereupon spring 24 may be slipped over the spindle into engagement with projection 19. The front end of the spindle is then slipped through the opening in escutcheon plate 12 and the latter secured in 35 position against the front of rail 5. Flange 11 and plate 12 will lie in the counter-sunk opening at the front of the rail, so that plate 12 will lie flush with the front of the rail, in which position it may readily be secured 40 by suitable screws.

The knob 20 may then be slipped on the front end of the spindle and fastened in position by screw 22. An opening 32 may be provided in the sleeve 23 through which 45 screw 22 may be dropped into position to secure the same through the spindle and into flange 21 of the knob, this being possible when the knob and spindle are pulled forwardly to the extreme position shown in 50 Fig. 4.

The horizontal opening 8 in rail 4 may then be bored, in position to aline with opening 9, and the lining member 25 fastened in position by screws 33. The guide slot 55 7 is then rabbeted out and the metallic guide slot member fastened in position by means of screws 34 which extend through the bottom portion 27 of the metallic guide slot member into the stile of the sash.

60 The lock construction may very readily be removed from the sash by taking out the screws by which the escutcheon plate 12 is positioned, after which the knob is removed by unscrewing screw 22 through 65 opening 32. The screw which holds barrel

flange 11 in position is then removed which permits removing the entire lock construction from the sash rail 5. The spindle may then be slipped forwardly out of the barrel 10 whereupon the spring 24 may be removed. 70

It should be understood that my invention is not limited strictly to the details of construction described but is as broad as is indicated by the accompanying claims.

What I claim is:—

1. In window construction, the combination of upper and lower sliding sashes, having horizontal openings through the frame of the lower and extending into the frame of the upper sash, respectively, adapted to aline when both sashes are closed, said upper sash opening having a locking socket extension, the upper sash having a vertical guideway of length less than that of the sash and communicating with said upper sash opening, a barrel in said lower sash opening, having a keyhole slot therein, a spindle mounted in said barrel, having a head adapted to be inserted in said socket extension, or alined with said guideway, or positioned in front of said guideway, in non-obstructing position, when said horizontal openings are alined, said spindle having three spaced projections of which two, one, or none, are adapted to pass through said slot, in one angular position of said spindle, and in accordance with whether said head is in the first, second or third of the positions referred to, said projections being adapted to lock said spindle against axial movement, upon rotation of said spindle to a different angular position, in any of said three positions. 95

2. In window construction, the combination of upper and lower sliding sashes, a stile of the upper sash having a vertical guideway extending part only of the length thereof, a horizontal opening through the frame of the lower sash, a spindle mounted for axial and rotational movement in said opening and adapted to extend beyond each end thereof, a head on the end of the spindle adjacent the upper sash, and means for locking said spindle against axial movement in said opening with said head alined with said guideway, said means comprising a slotted flange carried by the lower sash and a projection on said spindle adapted to engage said flange and adapted upon predetermined rotational movement of said spindle to pass 110 through the slot of said flange. 115

3. In window construction, the combination of upper and lower sliding sashes and a recess in said upper sash, a horizontal opening through the frame of the lower sash adapted to register with said recess, a spindle mounted for axial and rotational movement in said opening, a head on said spindle, and means for locking said spindle against axial movement in said opening 125 130

with said head seated in said recess, said means comprising a slotted flange carried by the lower sash and a projection on said spindle adapted to engage said flange and adapted upon predetermined rotation of said spindle to pass through the slot of said flange.

This specification signed and witnessed this 19th day of October, 1920.

CHARLES ALBONESI.
